CLAIM

The ornamental design for an absorbent article package, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective front, top perspective view of an absorbent article package showing the new design;

FIG. 2 is a front view of the design shown in FIG. 1;

FIG. 3 is a right side view of the design shown in FIG. 1;

FIG. 4 is a back view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines in the drawings depict portions of the absorbent article package that form no part of the claimed design.

1 Claim, 4 Drawing Sheets
(2 of 4 Drawing Sheet(s) Filed in Color)

Related U.S. Application Data

division of application No. 29/482,126, filed on Feb. 14, 2014, now Pat. No. Des. 744,333.
